UNITED STATES PATENT OFFICE.

JAMES N. HENRY, OF PROVIDENCE, RHODE ISLAND.

BRACKET FOR CURTAIN-RODS.

1,156,076.

Specification of Letters Patent.

Patented Oct. 12, 1915.

Application filed March 22, 1915. Serial No. 16,043.

To all whom it may concern:

Be it known that I, JAMES N. HENRY, a citizen of the United States, residing at Providence, in the county of Providence and State of Rhode Island, have invented certain new and useful Improvements in Brackets for Curtain-Rods, of which the following is a specification.

My invention relates to supports or brackets for curtain rods, especially for those having ends disposed at an angle to the plane of the body.

The essential objects of my invention are facility of engagement and disengagement of the parts combined with security when in use, and inexpensiveness of construction.

A further object is to insure the capacity of the supports for angular arrangement of the bases of the supports relatively to the ends of the rods.

To the above ends essentially my invention consists in such parts and combinations of parts as fall within the scope of the appended claim.

In the accompanying drawings which form a part of this specification, and wherein like characters of reference indicate like parts throughout the views, Figures 1 and 2 are plan and front elevations respectively of my novel brackets engaging the ends of a curtain rod which is shown partially broken away, Fig. 3, a section of the same on line *xx* of Fig. 2, and Fig. 4, a perspective view of the bracket member.

Each bracket comprises a base *A* provided with perforations *a* adapted to receive attaching screws *b* for attachment to a window moulding *B*. The central portion of the base is preferably elevated as at *c*, and is provided with spaced perforations *d* to receive lugs *e* upon the end of the plate *E*. The lugs *e* are riveted or bent over against the inner face of the base *A* and retain the plate *E* in tight engagement with the base. The plate *E* is provided with an ob-

long rectangular longitudinally disposed slot *f* extending from a point near its attachment with the base to the end of the plate. This slot divides the plate so as to produce two parallel flat resilient arms *G* provided with rounded or beveled end portions *g*. In the exterior edges of these arms at the ends of the beveled portions are oppositely disposed notches *h*.

The curtain rod in the present instance comprises two telescoping sections *J* having curved end portions and provided near their ends in each instance with an internal annular rib or shoulder *k* adapted to register in the notches *h* of the arms *G*, when the rods abut against the raised portion *c* of the base *A*. The resiliency of these arms permit their compression toward each other as the end of the rod advances over the beveled portions of their ends, and permits the seating of the rib in the notches in such a manner that the rod cannot accidentally be removed.

It will be noted that this construction avoids the use of solder and that the whole may be stamped from thin sheet metal.

What I claim is:—

The combination with a curtain rod provided with an internal rib, of a bracket comprising a base, provided with an elevated central portion, and with perforations in said central portion, a plate upon the elevated portion of the base having lugs passing through the perforations in the base and engaged with the rear face of the base, and compressible arms upon the plate adapted to engage the rod and provided with notches adapted to receive the rib of the rod.

In testimony whereof I have affixed my signature in presence of two witnesses,

JAMES N. HENRY.
